DESIGN FOR A PORTABLE ELECTRIC RECTIFIER

Dave Chapman, Chicago, Ill., assignor to P. R.
Mallory & Co., Inc., Indianapolis, Ind., a cor-
poration of Delaware

Application May 23, 1946, Serial No. 130,026

Term of patent 7 years

(Cl. D26—5)

To all whom it may concern:

Be it known that I, Dave Chapman, a citizen
of the United States of America, residing at Chi-
cago, in the county of Cook and State of Illinois,
have invented a new, original, and ornamental
Design for a Portable Electric Rectifier, of which
the following is a specification, reference being
had to the accompanying drawing, forming part
thereof.

Figure 1 is a perspective view of a portable
electric rectifier showing my new design; and

Figure 2 is a side view thereof.

What is claimed is:

The ornamental design for a portable electric
rectifier, as shown.

DAVE CHAPMAN.
